UNITED STATES PATENT OFFICE

JOHN KRUSI, OF NEW YORK, N. Y.

DESIGN FOR EMBROIDERY

Application filed September 16, 1931. Serial No. 41,122. Term of patent 3½ years.

To all whom it may concern:

Be it known that I, JOHN KRUSI, a citizen of the United States, residing at New York, in the county of New York and State of New York, have invented a new, original, and ornamental Design for an Embroidery, of which the following is a specification, reference being had to the accompanying drawing, forming part thereof.

The figure is a plan view of an embroidery, showing my new design.

I claim:

The ornamental design for an embroidery, as shown.

JOHN KRUSI.
